CONTAINER

Sante Joseph Ferrante, Passaic, N. J.

Application January 16, 1940, Serial No. 314,155

1 Claim. (Cl. 229—55)

The present invention relates to new and useful improvements in containers particularly for the reception of shirts and other articles in laundries but it will be understood, of course, that the invention may be used for any other purpose for which it may be found adapted and desirable.

The primary object of the invention is to provide, in a manner as hereinafter set forth, a container of the aforementioned character comprising novel means for reinforcing or strengthening the ends of said container.

Another very important object of the invention is to provide a container of the character described which is adapted to be folded or collapsed in a manner to require a minimum of space.

Still another very important object of the invention is to provide a container of the character set forth wherein foldable or collapsible paper bags may be used.

Other objects of the invention are to provide a container for shirts and other articles which will be comparatively simple in construction, strong, durable, highly efficient and reliable in use, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a perspective view of a container constructed in accordance with the present invention, showing said container closed.

Figure 2 is a perspective view, showing the container open.

Figure 3 is a perspective view, showing the mouth of the bag open but with the closure member in closed position, a corner portion of the device being broken away in section.

Figure 4 is a perspective view, showing the container in folded or collapsed position.

Figure 5 is a view in vertical longitudinal section through the container.

Figure 6 is a detail view in perspective of the foldable closure member.

Figure 7 is a detail view in perspective of the bottom or closed end reinforcing element.

Referring now to the drawings in detail, it will be seen that the embodiment of the invention which has been illustrated comprises a bag of paper or other suitable material which is designated generally by the reference numeral 1, said

bag being of any desired dimensions. The bag 1 is provided with a closed end or bottom 2, the other end or mouth of said bag being open. As shown to advantage in Figure 4 of the drawings, the bag 1 is adapted to be folded or collapsed in a conventional manner. The end 2 of the bag 1 has adhesively or otherwise secured therein a reinforcement 3 of cardboard, heavy paper or other suitable material.

10 Mounted in the mouth portion of the bag 1 but spaced from the open end thereof is what may be referred to as a closure which is designated generally by the reference numeral 4. The closure 4 is of cardboard or other suitable material and comprises an integral, marginal flap 5 which is firmly secured in any suitable manner, as by gluing or stapling, to the inner side of the wall 6 of the bag 1. On the free end of the closure 4 is an integral fold 7. At the fold 20 line 8 of the elements 4 and 7 is a finger receiving opening 9.

The wall 6 of the bag 1 has formed, in the mouth portion of said bag, an opening or eyelet 10. The opening or eyelet 10 is for the reception 25 of a fastener 11 on the outer side of the wall 12 of the bag 1.

It is thought that the manner in which the container is used will be readily apparent from a consideration of the foregoing. Briefly, to fold 30 the container, the closure 4 with the fold 7 thereon is swung downwardly on the wall 6 in the bag 1 to the position suggested in dotted lines in Figure 5 of the drawings. With the closure 4 in this position the bag 1 may be readily folded 35 or collapsed in the manner illustrated in Figure 4 of the drawings. When shirts or other articles are to be inserted in the container the bag 1 is opened and the closure 4, with the member 7 in folded position thereon, is swung outwardly 40 and downwardly to the position illustrated in Figure 2 of the drawings, the opening 9 facilitating this operation. The shirts or other articles may now be conveniently inserted, after which the member 4 is swung to the position

45 shown in Figure 3 of the drawings. Then, the mouth portion of the bag is closed and secured by inserting the fastener 11 through the eyelet 10. It may be well to here state that other suitable means may be employed for securing the 50 mouth portion of the bag in closed position.

When the container is in folded or collapsed position the fastener 11 is preferably flattened out or spread in order to be out of the way.

It is believed that the many advantages of a container constructed in accordance with the

present invention will be readily understood and although a preferred embodiment of the device is as illustrated and described, it is to be understood that changes in the details of construction may be resorted to which will fall within the scope of the invention as claimed. For example, the invention also contemplates the use of paper bags with cardboard inserts with mere folding of the edges of the bags.

What is claimed is:

A container comprising a collapsible bag open at one end, a closure mounted for swinging movement in the bag adjacent the open end thereof, said closure being of cardboard and including an integral flap on one end secured flatwise to one

5 wall of the bag in a transverse position, said closure embodying an intermediate section and a free end section coextensive with the intermediate section and foldable against each other, said free end section being adapted to edgewise abut the flap when the closure is in a transverse position for closing the container, said intermediate and free end sections having an opening in their connecting portion and said intermediate and free end sections of the closure being 10 adapted for arranging in extended relation and foldable in extended form on said flap inwardly of the container.

SANTE JOSEPH FERRANTE.
